SACK PACKER

William T. Shaler, Silver Creek, N. Y.

Application April 22, 1932. Serial No. 607,000

4 Claims. (Cl. 259—72)

The invention relates to vibrating or jolter packers which are used to pack mill feeds or similar products into sacks, and it aims to provide a new and improved packer having novel means for supporting and vibrating the sack support, in such manner that said support moves only in a vertical direction, instead of having any rocking motion tending to loosen the material in the sack.

With the foregoing in view, the invention resides in the novel subject matter hereinafter described and claimed, description being accomplished by reference to the accompanying drawings.

Fig. 1 is a side elevation of a packer constructed in accordance with my invention.

Fig. 2 is a vertical longitudinal sectional view substantially on line 2—2 of Fig. 3.

Fig. 3 is a rear elevation.

Fig. 4 is a rear elevation of the machine frame.

Fig. 5 is a perspective view of the vibratory lever instrumental in carrying and vibrating the sack support.

Fig. 6 is a detail vertical sectional view showing a somewhat modified construction.

The specific embodiment of the invention, selected for illustration in the present application, will be described in detail, with the understanding however that within the scope of the invention as claimed, numerous minor variations may be made.

The machine embodies a rigid frame 10, a sack support 11 upon which a filled bag rests unsecured, a lever 12 fulcrumed at 13 to the frame 10 and pivoted at 14 to the sack support 11, linkage 15 connecting an upper portion of the sack support 11 with the frame 10, and means mounted on the frame and connected with the lever 12, for rapidly oscillating or vibrating the latter vertically, sufficiently to pack the sack contents but with insufficient violence to upwardly throw the sack, or to upwardly throw its contents. The portion of the lever 12 in advance of its fulcrum 13, and the linkage 15, constitute parallel linkage of fixed length which insures that the movement of the sack support 11 shall be truly vertical, with no rocking motion, better packing results being thus obtained.

The frame 10 embodies two side members or frames 16 tied together at their lower ends by a rod 17 and an angle bar 18, tied together between their upper and lower ends by angle bars 19, 20 and 21, and tied together at said upper ends by an angle bar 22.

The lever 12 is disposed between the lower ends of the side members 16, and said lever may be of the construction detailed in Fig. 5. From this

view primarily, it will be seen that lever 12 embodies two parallel side members 23 connected near their front ends by a transverse bar 24, connected at their rear ends by a transverse bar 25, and connected near said rear ends by another transverse bar 26. Short webs 27 extend between the bars 25 and 26, and the lower ends of vertical pitman or connecting rods 28, are received between said webs and the side members 23, being pivoted thereto as indicated at 29. The upper ends of the pitman or connecting rods 28 are engaged with eccentrics or cranks 30 on a transverse shaft 31 which is mounted in appropriate bearings 32 on the rear portion of the frame 10. This shaft is driven by means of an electric motor 33 mounted upon an appropriate supporting frame 34 carried by the frame 10, a belt 35 and co-acting pulleys being shown for operatively connecting the motor with the shaft. The eccentrics 30 have only sufficient throw to effect vibration for sack packing and their throw is insufficient to upwardly throw the sack from the support 37 or to upwardly throw the sack contents.

The sack support 11 is preferably of the L-shape shown, and it may well consist of a frame 36, a sack supporting plate 37 secured horizontally upon said frame, and a back plate 38 against which to rest the sack, said back plate being secured to said frame. In the construction shown, this frame embodies a horizontal bar 39 spaced forwardly from the bar 22, the linkage 15 being connected to these two bars. This linkage is shown in the form of horizontal spring metal strips of fixed length whose rear ends are clamped at 40 upon the bar 22 and whose front ends are similarly clamped at 41 upon the bar 39. If desired however, other linkage of fixed length such as 15^a of Fig. 6 may be employed, pivoted at 40^a to the bar 22 and pivoted at 41^a to the bar 39.

When the shaft 31 is driven by the motor 33, the eccentrics 30 and rods 28 rapidly oscillate or vibrate the lever 12 and said lever imparts this vibratory motion to the sack support 11. Hence, the contents of any sack placed upon this support will be so jolted as to be effectively packed. Due to the mounting of the sack support 11, its vibratory movement will be truly vertical and greater efficiency will thus be obtained than with supports which are moved vertically and at the same time rocked, for such rocking motion has a tendency to more or less defeat the packing produced by the vertical motion.

I claim:—

1. A sack packer comprising two laterally spaced vertical side frames, an elevated horizon-

tal bar extending between and secured to said side frames, a horizontal transverse rod extending between and carried by said side frames in downwardly spaced relation with said horizontal bar, 5 a lever of fixed length between said side frames and fulcrumed between its ends on said rod, said lever having two longitudinal side members, an L-shaped sack support frame and means pivoting this frame to the front ends of said lever side 10 members on an axis parallel with said rod and said elevated bar, the vertical portion of said L-shaped sack support frame having a horizontal elevated bar parallel with and forwardly spaced from the aforesaid elevated bar, substantially horizontal linkage of fixed length extending between and connected to said elevated bars, a horizontal sack-support carried by the horizontal portion of said L-shaped sack support frame, a vertical wall at the rear edge of said sack support and secured to 15 20 said vertical portion of said sack support frame, said sack support and wall serving to support a filled sack in vertical position without necessity of securing the sack, a shaft extending between said side frames over the rear end of said lever, 25 said shaft being provided with two eccentrics spaced apart in the direction of their axis, pitmen connecting said eccentrics with the rear ends of said lever side members, and means for driving said shaft, said eccentrics having only sufficient throw to effect sack packing without upwardly throwing the sack or its contents.

2. A sack packer comprising a rigid frame, a sack support having a horizontally extending lower sack supporting portion and a vertically extending upper frame portion, a vertically swingable lever of fixed length fulcrumed on said frame and pivoted to a lower portion of said sack support, vertically swingable linkage of fixed length connecting an upper portion of said sack support 30 with said frame, said linkage being substantially

parallel with said lever, and means mounted on said frame and connected with said lever for rapidly vibrating the latter sufficiently to pack the sack contents but with insufficient violence to upwardly throw the sack or its contents. 80

3. A sack packer comprising a rigid frame, a sack support having a horizontally extending lower sack supporting portion and a vertically extending upper frame portion, a vertically swingable lever of fixed length fulcrumed between its 85 ends on said frame and pivoted at its front end to a lower portion of said sack support, vertically swingable linkage of fixed length connecting the upper portion of said sack support with said frame, said linkage being substantially parallel 90 with said lever, an eccentric-carrying shaft mounted rotatably on said frame near the rear end of said lever, and a pitman connecting the eccentric of said shaft with said rear end of said lever, said eccentric having sufficient throw to 95 vibrate said lever and sack support to pack the sack contents but having insufficient throw to affect upward throwing of the sack or its contents.

4. A sack packer comprising a rigid frame, a sack support having a horizontally extending lower sack supporting portion and a vertically extending upper frame portion, a vertically swingable lever of fixed length fulcrumed on said frame and pivotally connected with said sack support, vertically 100 swingable linkage of fixed length pivotally connected with said sack support and with said frame, said linkage and lever being substantially parallel and being connected with said sack support at vertically spaced points, and means mounted 105 on said frame and connected with said lever for vertically vibrating the latter sufficiently to pack the sack contents but with insufficient violence to upwardly throw the sack from said support. 110
